[57] CLAIM

The ornamental design for a hand scraper, as shown and described.

DESCRIPTION

FIG. 1 is a top, front and side perspective view of a hand scraper embodying my new design;
FIG. 2 is a side elevation view of the hand scraper of FIG. 1 from the opposite side of that shown in FIG. 1;
FIG. 3 is a top plan view thereof;
FIG. 4 is a front elevation view thereof;
FIG. 5 is a rear elevation view thereof; and
FIG. 6 is a bottom plan view thereof.
